OTHER PUBLICATIONS

U.S. Appl. No. 29/318,930, filed May 30, 2008, by Lawrence A. Bone et al., entitled "Packaging".

* cited by examiner

Primary Examiner—T. Chase Nelson

Assistant Examiner—Karen Acker

(74) *Attorney, Agent, or Firm*—Arent Fox LLP

(57) **CLAIM**

The ornamental design for the packaging, as shown and described.

DESCRIPTION

FIG. 1 is a perspective view of a packaging showing our new design;

FIG. 2 is a front view of the design shown in FIG. 1;

FIG. 3 is a rear view of the design shown in FIG. 1;

FIG. 4 is a top view of the design shown in FIG. 1;

FIG. 5 is a bottom view of the design shown in FIG. 1;

FIG. 6 is a left side view of the design shown in FIG. 1; and,

FIG. 7 is a right side view of the design shown in FIG. 1.

The broken lines in FIGS. 1, 6 and 7 illustrate fold lines and form part of the claimed design.
